SPARK PLUG

Application filed October 5, 1928. Serial No. 310,528.

My invention relates to ignition devices, and particularly to spark plugs; and it has for its object the production of an improved spark plug adapted to all types of internal combustion engines, especially those of unusually high compression and of the air cooled type.

To operate with efficiency in such engines, a spark plug must be perfectly gas tight in all its parts, especially under the high heat and high pressures generated when full charge is supplied at a wide open throttle under heavy loads. The insulator must retain its original dielectric strength at the highest working temperatures, or the relatively high current which is vitally needed to completely ignite the present day dense fuels, will be diverted away from the spark gap, through leakage, and insufficient heat from a weak spark will cause incomplete combustion with great loss of efficiency. There are two types of spark plug in general use, viz: the open end type, and the so-called baffled type. The open end type is the most popular, being the least expensive, with an unobstructed heat path which in operation must be permitted to become sufficiently hot to convert the impinging mass of motor fuel and oil into gas. Thus it will remain clean, but if allowed to overheat the tip becomes incandescent and pre-ignition will result. Accordingly, standard spark plugs are made with many variations in the heat path length and the shoulder position of the insulator or core. The lower the shoulder in the shell the more quickly is the heat permitted to escape through the thread section of the shell which is threaded into a metal boss in the cylinder and usually surrounded by the circulating cooling water. If the heat path is short, and the shoulder is lower than the shell, then the heat escapes too quickly, with the result that the heat path does not operate at high enough temperature but merely distills off the lighter fractions of the gasoline vapor, leaving the carbon attached to itself. With such operation, surface shortage occurs, with consequent missing of the engine.

Two conditions exist today which are especially difficult to meet for the proper op-

eration of spark plugs. One is the gradually increasing B. t. u. content of the cracked gasolines on the market, which has risen in seven years from 18,000 B. t. u.'s per pound in the old "straight run" fuels, to nearly 21,000 B. t. u.'s in the midwest fuels. None of these new fuels are as volatile or as easily vaporized or as readily ignited as the old type fuels, and they all burn at considerable higher temperatures. Added to this, many American engine manufacturers have adopted the European system of high compression, which is becoming common. The result is still higher temperature developments, and higher working pressures, which make it more difficult to operate with the old type of plug. In these plugs, the steel shell with its expansion coefficient very much higher than that of the porcelain core, simply runs away from its seat, and leakage of the burning gases increases the core temperature to a point where its dielectric strength is so badly broken down that it becomes a comparatively good electrical conductor and so much current is shorted out that incomplete combustion is the rule.

The second type of plug I may call the "baffled" type. Examples of this type are found in the following U. S. Letters Patent among others: Tidmarsh, No. 1,008,219, Nov. 7, 1911; O'Gara, No. 1,286,074, Nov. 26, 1918; Colby, No. 1,374,281, Apr. 12, 1921; Brewster, No. 1,390,014, Sept. 6, 1921; Margolin, No. 1,397,321, Nov. 15, 1921; Aschinger, No. 1,419,197, June 13, 1922; Pethoud, No. 1,450,987, Apr. 10, 1923; Rasmussen, No. 1,497,985, June 17, 1924.

It will be noted that in all of the patents cited, the baffle or baffles, and especially those attached to the central stem, are set low down and adjacent to the opening in the end of the shell. Wherever the baffle is attached to the lower end of the central electrode, it causes preignition at wide opened throttle combustions, for there is no provision to carry off the heat accumulated in a relatively large baffle, or in other words there is no provision of a heat gradient to carry the heat quickly enough to the shoulder and there dissipate it through the shell into the circulating water.

Furthermore, in both baffled and open ended plugs, there is insufficient provision for maintaining the opening through the insulator core and around the central stem gas tight. 5 With the old plugs the engine that is operated at low speeds generates so little heat that the heat paths run cold with resulting surface shortage and cutting out. In both types, the center assembly of the electrode wire, which is about 90% nickel, and which is lightly cemented in the core, so that its expansion will not split the core, may leak, and if more thorough cementing is resorted to splitting of the core invariably results, 10 which is generally disastrous to the engine or valves.

In the present plug, there are six primary elements: body, gland, insulator, spindle, a series of deflectors or baffles, and a series of 20 high expansion sleeves. Two of the baffles are carried on the gland assembly and an intermediate baffle is attached to the central spindle. All of these baffles are set up high in the chamber or heat path, the central 25 baffle in particular being protected so that it cannot become hot enough to cause pre-ignition. Special valved means are provided for maintaining all joints proof against leakage, no matter what the temperature or pressure, so that these plugs are especially adapted to high compression engines using modern motor fuel.

My invention is illustrated in the accompanying drawing, in which the figure is an 35 axial longitudinal section of my improved plug.

Referring to the drawing, 1 is the body or shell, which may be of any suitable metal or alloy, internally threaded at 7 to receive the 40 assembly gland and externally threaded at 8 for screwing into the engine. 2 is the insulator or core, which may be made of a suitable ceramic material, or of mica. It is accurately ground to form a shoulder 15 at a 45 predetermined angle and is ground at right angles to the axis of its longitudinal bore 20, on both ends, for a purpose which will be presently described. 3 indicates the assembly gland, which is of metal, with a shoulder 50 at 15 corresponding to the shoulder of the core and ground exactly to the same angle. It has an external thread engaging the internal thread of the casing or shell at 7. 9 indicates the central spindle, which is of alloy steel or in case of high temperature air 55 cooled engines is of copper or other metal or alloy of high thermal conductivity with a head 11 formed on it, and an electrode 9a buttwelded to said head, or integral with it.

17 and 19 indicate annular baffles shown in section, both of copper or other suitable material. 18 indicates a central baffle which is of the same metal as the electrode 9a, to 60 which it is permanently attached or with

which it is integral, as for example formed thereon by cold pressing.

4 and 5 indicate the high expansion sleeves hereinbefore referred to. These are two cylinders of exact diameter to fit within the 70 gland 3 with the horizontal flange of the baffle 17 clamped between them. The manner of their assembly will presently be described. The spindle 9 at its upper end is screw threaded, and carries a spring washer of 75 steel, indicated by the numeral 13, and a lock nut 14. Electrical connection from the dry or ungrounded side of the spark coil may be by the usual nut or nuts on the threaded end of the spindle, outside of nut 14, or any 80 appropriate form of clamp or connector may be used. The spring washer 13 sets closely against the ground outer face of the insulator 2, and the head 11 on the spindle sets closely to the ground inner face of the insulator, with a thin annealed copper gasket 12 interposed between the contiguous faces. Sufficient clearance is left in the bore of the insulator to permit expansion and contraction of the spindle without cracking the insulator, and when the nut 14 is set up tightly, the respective washers resting against the two ground faces of the insulator and backed by the nut 14 and the head 11 constitute valves which effectually prevent leakage of the hot 85 gases through the insulator and around the 90 spindle.

Assembly

The insulator 2 having been prepared by 100 grinding, is inserted in the assembly gland 3 with a thin annealed copper washer between the two shoulders 15—16 and is pressed to a seat, thereafter acting as a valve to prevent leakage. The sleeve 4 is then inserted in the assembly gland, the annular baffle 17 is in turn seated upon said sleeve and then the spindle 9 is inserted in the insulator with its thin copper washer between the head 11 and the ground face of the insulator and is 105 held to a seat by means of the nut 14 resting against the spring washer 13, which in turn bears against the ground upper end of the insulator, these parts thereafter acting 110 also as a valve to prevent leakage.

The sleeve 5 is then inserted, and the lower edge of the assembly gland is swaged over the edge of the sleeve 5, as shown at 6 in the drawings. This completes the assembly 115 gland, with all its parts. The baffle plate 123 or deflector 19 is then dropped into the bottom of the upper opening in the shell 1 and the gland is screwed down upon the same by means of thread 7, the entire assembly being turned up by means of said threads.

Operation

The operation of my improved plug in an engine is as follows: Should there be an abundance of rich vapor, or oil charged va- 120

por working upward toward the interior of the plug, the first baffle or deflector 19 is met and the greater quantity of said vapor is deflected downward or outward. Since the 5 orifice in the deflector 19 is materially smaller in area than the open end of the shell 1 in the engine, only a very small quantity of the vapor or oil finds its way to the interior of the plug. The portion which does enter 10 however, meets the second deflector or baffle 18 secured on the electrode end of the spindle and is also deflected downward or outward, and by this means the insulator 2 being located considerably higher up, is never affected 15 by the carbon in the vapor. Further protection is afforded by the baffle or deflector 17, which in case oil or vapor does penetrate so far, continues the action of the two lower deflectors.

20 It will be noted that the method of assembling the insulator in the assembly gland, forms a valve on a valve seat, at 15—16, and while at normal temperatures the seat pressure is light this pressure increases exactly 25 in proportion to the pressures of the gases in the engine, maintaining a tight joint and absolutely avoiding leakage at this point. It may be noted however, that there is a difference 30 in the co-efficient of expansion of the materials of the insulator 2 and the gland 3, which may be of say, porcelain and brass, respectively. Such a difference might result 35 in opening of the valve due to over expansion of the gland 3, and to prevent this I have made the following provision: the two sleeves 4—5 are made of aluminum or alloy 40 aluminum with a considerably higher coefficient of expansion than the brass. Hence the expansion of these sleeves, acting between 45 the shoulder 6 of the gland 3, and the lower face of the insulator 2, tends to force the insulator upward and to maintain its shoulder seated snugly against the ground shoulder of the gland, at 15—16. By careful calculation, these parts can be made to proportionally increase the pressure on the insulator seat 15—16, in exact ratio with the difference 50 in expansion of the two dissimilar materials mentioned, and a perfect gas tight seat is the result at all times and under all conditions of heat and pressure.

In this connection, it should be noted that a very important part of my invention, lies 55 in building the deflector or baffle 18 integral with and locating it at the proper point on the electrode 9a; for while there have been spark plugs with deflectors or baffles attached to the lower end of the electrodes or spindles, for the purpose of keeping oil out of the 60 interior of the plug, none of these to my knowledge have been successful for the reason that being exposed, the heat absorbed by these rather large masses of metal cannot be carried away quickly enough through the spindle, and as a consequence, at wide open throt-

tle running, while the maximum temperatures are developed, they become incandescent, and preignition invariably results. But with the baffle or deflector 18 placed as shown in my plug, it is far enough away from the heat to escape this very serious fault. Specifically, 70 the baffle 18 is located near the upper end of the electrode, approximately one-fourth of the length of the electrode from the insulator, and it is protected by the lower baffle 19 within and above which it lies. All three of my baffles 17, 18, 19, it will be observed, lie above the middle point, or approximately the middle point of the electrode 9a, so that approximately one-half of the heat path surrounding 75 and above the electrodes 9a—10 is clear of obstruction, and there is no possibility of the baffle 18 becoming over heated or incandescent.

What I claim is:

1. A spark plug comprising the following instrumentalities: a tubular metal shell, a tubular metal gland fitted within one end of said shell, an insulator fitted in the outer end of said gland so as to leave an extended 85 heat path within the same and the shell in length not less than twice its own diameter, a metal spindle extending through the insulator, an electrode secured to said spindle and extending through said heat path axially of the shell to the open end thereof, an annular deflector or baffle secured in said shell approximately midway of the length of said heat path, surrounding said electrode with clearance between them, and a second annular baffle secured on said electrode between 90 said first baffle and said insulator, together with a return spark member for said electrode, at the open end of the shell.

2. The spark plug described in claim 1, in which the second baffle plate is approximately midway between the insulator and the first baffle and is conical in shape with its skirt extending downwardly and outwardly from the upper part of the electrode, 105 so as to cover the clearance opening between the first baffle and said electrode, said first baffle being also approximately conical, with its sides extending inwardly and downwardly toward the electrode, but out of contact 110 therewith.

3. The spark plug described in claim 1, having the insulator formed with a ground joint or the equivalent at the points of its engagement with the gland, and with equivalent gas tight joints at the inner and outer ends of the spindle, adapted to close together 120 in the direction of and in response to pressure thereon whereby all joints are maintained against leakage, at all temperatures and pressures.

4. The spark plug described in claim 1, having a third deflector or baffle similar to the first, with its outer edges secured in the gland above the second baffle, and with its 125

inner edge surrounding the electrode between said second baffle and the spindle head.

5. A spark plug comprising the following instrumentalities: a tubular metal shell, a tubular metal gland fitted therein, an insulator fitted in the upper end of said gland, so as to leave a heat path extending through the greater part of the length of said shell, its own length being not less than twice its 10 diameter, a spindle extending through said insulator, an electrode forming a continuation of said spindle and extending through said heat path axially of the shell to the outer end thereof, and a plurality of metal deflectors or baffles, all set high up in the chamber or heat path, one of said baffles being secured to said electrode, and protected by a lower baffle surrounding the electrode and having a clearance therefrom of less than 15 the diameter of the protected baffle, so that said baffle cannot become hot enough to cause preignition.

6. The spark plug described in claim 5, in which the baffle attached to the electrode 25 is intermediate of two other baffles both surrounding the electrode with an annular clearance therefrom, and having their outer edges clamped in the assembly of the gland and the shell.

30 7. The spark plug described in claim 5, in which the insulator is shouldered, the gland is similarly shouldered with accurately fitting surfaces, to form a valve and seat, with means to maintain said valve shoulder 35 pressed against its seat under variable conditions of temperature and pressure, to prevent leakage.

8. The spark plug described in claim 5, in which the insulator is shouldered, the 40 gland is similarly shouldered with accurately fitting surfaces, to form a valve and seat, with means forming a part of the gland assembly constructed of metal having a higher coefficient of expansion than that of the 45 gland, said means acting against the lower face of the insulator, to force the latter up as the temperature rises, and by the difference in expansion to compensate for expansion of the body of the gland, whereby the 50 valve shoulder on the insulator is maintained in close contact with its seat shoulder on the gland.

9. A spark plug comprising the following instrumentalities: a tubular shell having an 55 internal shoulder, an assembly gland fitting within said shell above said shoulder, an inwardly turned flange formed on the outer end of said gland, an insulator shouldered to fit the shoulder on the gland, and having 60 its body extending only part way through the bore of said gland, expansion means inserted within the open end of the gland below the insulator, and means upon said gland engaging said expansion means to hold the same 65 against said insulator, the metal of said

gland and the metal of said expansion means having different coefficients of expansion.

10. The spark plug described in claim 9, having the expansion means formed in sections, with an annular deflector or baffle 70 surrounding the central electrode and having its outer edge clamped between the sections of said expansion means.

11. The spark plug described in claim 9, in which the gland assembly includes the 75 gland itself, the insulator shouldered to project from the upper end thereof, expansion means inside the gland to hold the insulator in position, and a flange on the gland swaged over on said expansion means to hold the 80 same rigidly in position.

12. A spark plug comprising a shell, an insulator seated in said shell, and holding means for said insulator comprising elements having different coefficients of expansion, 85 adapted to exert pressure oppositely on said insulator, and adjusted so that said opposite pressures will always balance and maintain the joint or joints around the insulator gas 90 tight.

13. A spark plug comprising a shell, an insulator secured gas tight in said shell, an opening through said insulator, a conducting spindle passing through said opening, an electrode carried by said spindle, and means 95 on said spindle responsive to changes in pressure within the shell to maintain said opening through the insulator sealed gas tight under all conditions.

14. A spark plug comprising the following 100 instrumentalities: a tubular shell internally shouldered about midway of its length, an annular metal deflector or baffle having its outer edges resting on said shoulder, and an assembly gland screwed into the enlarged bore 105 of the shell against said baffle, said assembly comprising a tubular metal gland internally shouldered at one end, a shouldered insulator projecting from said end, with a shoulder 110 engaging the gland shoulder, a spindle extending through said insulator axially with the shell, an electrode forming a continuation of said spindle and extending through the shell to the open end thereof, a metal expansion tube inside the gland below the insulator, means at the lower end of the gland engaging 115 said expansion tube to hold it and the insulator in position, and a protecting baffle formed of metal integral with and projecting from the electrode above and within the first mentioned annular baffle, whereby it is protected from the heat of expansion and prevented from becoming incandescent and causing pre- 120 ignition.

15. A spark plug comprising a tubular shell, means for securing one end of said shell to the body of an engine, a shoulder within said shell, and an assembly gland together with a plurality of deflectors or baffle plates, 125 an insulator, a spindle in said insulator with 130

a continuing electrode extending through
said baffles, and adjustable means for secur-
ing said gland in the shell so arranged as to
tune up the entire assembly of gland, shell,
5 insulator and other parts in the gland and
between the gland and shell when the adjust-
ment is tightened.

In testimony whereof I hereunto affix my
signature.
